UNITED STATES PATENT OFFICE

WALTER SCHWEITER, OF HORGEN, NEAR ZURICH, SWITZERLAND

COP WINDING FRAME

Application filed December 4, 1930, Serial No. 500,126, and in Germany January 21, 1930.

The invention relates to winding frames and similar machines and has more particularly reference to a band brake for the unwinding bobbins of these machines.

5 In winding frames and similar machines uneven thread speeds arise in winding, according to whether the thread is running on to the point or on to the largest diameter of the bobbin, whereby variations in the tension 10 of the thread are caused. Consequently during a retardation, too much thread runs from the unwinding bobbin whereby entanglement and other disturbances are caused. To avoid this, the thread is guided 15 for instance on a thread guide which is adapted both to take up the variations in the tension of the thread and to exert a braking effect upon the unwinding bobbin by means of a band brake. This combination 20 of a thread guide with a band brake has generally proved effective, although the fineness of the mutual adjustment and the effect of the brake do not meet all possible events. Above all, the band brakes hitherto used are unable so to brake down the unwinding bobbin in an efficacious manner 25 upon a sudden lowering of the tension of the thread, that disturbances are excluded.

Now the invention has for its object to 30 overcome these drawbacks, which object is achieved primarily by the brake band employed being arranged so as to be swung about a fixed point, a spring accumulator being interposed which owing to its elasticity is adapted so to displace at least the one 35 point of suspension of the brake band in accordance with the power actuating the brake, that the brake band embraces a greater or smaller section of the periphery 40 of the brake disc. While hitherto the brake band whether attracted either by a great or by a small power, always touched the same section of the periphery of the brake disc, according to the invention the surface on 45 which the band and the disc touch one another, entirely depends upon the power employed, so that as long as only a small power is exerted, the braking surface is also small, while with increased braking 50 power the braking surface increases also,

whereby the braking effect becomes more efficacious and better adapts itself to the prevailing conditions.

In order to regulate the possibility of adjusting the braking effect in accordance with the thread material to be wound, the one fulcrum of the spring accumulator may be fixed to the one leg of a bell crank lever which is axially shiftable against the action 55 of a spring, while the other leg, which has the shape of a segment and is provided with notches or holes adapted to receive a fixed locking bolt, can be set in different positions, so that the fulcrum changes its position 60 relatively to the brake disc.

In order that the invention may be more readily understood, two embodiments of the same are illustrated by way of example in the accompanying drawings in which

Figure 1 is a lateral view of a brake forming the first embodiment,

Figure 2 is a view of the parts under consideration of a winding frame;

Figure 3 shows the upper portion of the Figure 2 with some parts in a different 75 position,

Figure 4 is a view similar to Figure 2 and shows the other embodiment, and

Figures 5 and 6 show the appurtenant braking device in side and end view, respectively, and on an enlarged scale.

Referring to these drawings, 4 denotes the unwinding bobbin on the shaft of which is rigidly mounted a brake disc 5. A preferably endless brake band 6 embraces a portion of the periphery of disc 5 which band is fixed with one end at 7 and with the other end at 8 to both ends of a resilient carrier 9 made from a steel strip. The carrier 9 constitutes the spring accumulator mentioned above and forms a loop at 10 by which it is hingedly fixed to a journal 11 while the other end of carrier 9 rests on a pull rod 12, Figure 1. As will be further seen from this figure, the two free ends of the brake band carrier 9 are bent off so as to have the brake disc 5 between them. The pull rod 12 is under the influence of the thread guide 13, Figures 2 and 3, which guides the thread 14 on the rollers 15 to the winding bobbin 16. 100

Figure 2 shows the thread guide 13 in the tensioned condition, which is the case when the pull of the thread acting in the direction of arrow α has increased. This position of guide 13 causes, by means of the connection of rod 12, the brake band 6 to assume the position shown relatively to the brake disc 5, in which position the brake band 6 is in contact with the latter only slightly or not at all. As soon as the pull of the thread 14 decreases, the thread guide 13 rises owing to its elasticity, about to the position illustrated in Figure 3. When this takes place, rod 12 entrains the brake so that a displacement of the fulcrum 7 and 8 is caused relatively to the brake disc 5, while the carrier 9 is elastically bent down. While thus in the position of the parts shown in Figure 2 the band 6 touched only a small section of the periphery of disc 5, it touches in the position of Figure 3 one third of the periphery of the latter. As to be seen, in this way the braking action is considerably increased without a greater power being required. A more efficacious braking effect can thus be obtained upon the unwinding bobbin 4 with one and the same braking power at disposal. As soon as the pull of the thread 14 increases again, the guide 13 lowers and the brake band 6 owing to the elasticity of carrier 9 assumes again its original position.

In order to enable an exact regulation of the braking action the journal 11 may be made adjustable. To this end as to be seen from Figures 4 to 6, the journal 11 is fixed to the one leg 17 of a bell crank lever 17, 19 which is fulcrumed at 18 and the other leg 19 of which forms a segment 21 having a series of holes 20. By means of an axially extending handle 22 lever 17, 19 can be shifted in an axial direction against the action of a spring 23. By these means the lever 17, 19 can be locked in position by a fixed bolt 24 engaging one of the holes 20, and released by retiring it on handle 22, whereupon it can be swung so that journal 11 can be raised or lowered, as indicated by arrows, Figure 5. In this way the position of the resilient carrier 9 and thus that of the brake band relatively to the brake disc 5 is altered, whereby the original braking action is increased or decreased, whilst the additional alteration of the braking action by means of the pull of the thread 14 is not influenced by this adjustment of journal 11.

It may be noted that the embodiments illustrated are merely examples of realization of the essence of the invention, which is not confined to these special designs. On

the contrary, various modifications are possible as to the arrangement of the brake and of the other parts as required by the various types of winding machines the invention is applied to, without deviating from the scope of the invention.

What is claimed is:—

1. In the combination of a band brake arrangement for an unwinding bobbin, a brake disc, a brake band in engagement with said brake disc, a carrier for said band having two arms across which said band extends a lever upon which said carrier is pivoted, means for adjustably setting said lever with respect to said brake disc, and means for varying the angular contact surface between said brake disc and band in accordance with the tension upon the thread unwound from the bobbin.

2. In the combination of a band brake arrangement for an unwinding bobbin, a brake disc, a brake band in engagement with said brake disc, a carrier for said band having two arms across which said band extends, a double armed lever mounted in the machine frame, upon which said carrier is pivoted, one of said arms of said lever carrying said pivoted joint of the carrier, and a plurality of locking apertures on the other arm adapted to cooperate with a locking bolt to selectively lock the double armed lever in different positions with respect to the brake disc, and means for varying the angular contact surface between said brake disc and band in accordance with the tension upon the thread unwound from the bobbin.

3. In the combination of a band brake arrangement for an unwinding bobbin, a brake disc, a brake band in engagement with said brake disc, a carrier for said band having two arms across which said band extends, a double armed lever axially and angularly movable in the machine frame upon which said carrier is pivoted, one of said arms of said lever carrying said pivoted joint of the carrier, and a plurality of locking apertures on the other arm adapted to cooperate with a locking bolt to selectively lock the double armed lever in different positions with respect to the brake disc, a spring for yieldingly maintaining said lever in locked position, means for axially shifting said lever to release the same from its locked position, and means for varying the angular contact surface between said brake disc and band in accordance with the tension upon the thread unwound from the bobbin.

WALTER SCHWEITER.
